Philip Braslawsky

By Frederick V. Winters,

Attorney

UNITED STATES PATENT OFFICE.

PHILIP BRASLOWSKY, OF NEW YORK, N. Y.

ONE-PIECE COAT.

1,361,820.

Specification of Letters Patent. Patented Dec. 14, 1920.

Application filed December 18, 1919. Serial No. 345,800.

To all whom it may concern:

Be it known that I, PHILIP BRASLOWSKY, a citizen of Russia, residing at New York, in the county of Bronx and State of New York, 5 have invented certain new and useful Improvements in One-Piece Coats, of which the following is a full, clear, and exact specification.

This invention relates to one-piece coats, 10 and has for its object to provide an improved pattern for cutting a coat from a single piece of material so that a minimum amount of material is required and a coat is produced which will be neatly fashioned, well fitting 15 and without exposed seams which would be apt to allow moisture to penetrate, for this pattern is especially designed for raincoats.

The invention will be first hereinafter described in connection with the accompanying 20 drawings, which constitute part of this specification, and then more specifically defined in the claims at the end of the description.

In the accompanying drawings, wherein 25 similar reference characters are used to designate corresponding parts throughout the several views:—

Figure 1 is a plan view of a piece of material cut according to my improved pattern. 30 Fig. 2 is a front view of the coat as it appears when the same is made up.

Fig. 3 is a rear view of the completed coat, and

Fig. 4 is a detailed fragmentary view of 35 the inner face of one of the lower corners of the coat.

In accordance with my improved pattern, the material is cut as shown in Fig. 1 so as to comprise a body portion 1, sleeve portions 40 2, breast portions 3 arranged above the sleeve portions, and pocket flaps 11 fashioned from the sleeve portions. A neck opening 4 is provided between the sleeve portions 2 and breast portions 3.

The body portion 1 has straight upper 45 edged portions 5 and curved edged portions 6 extending from the straight edges 5 to the sleeve portions 2. The upper parts of the lateral edges of the body portion are cut 50 away, as at 7, to correspond to the edges 8 of the breast portions 3. The sleeve portions 2 have cut-out portions 9 extending longitudinally thereof for reducing the fullness of the sleeves when the coat is made up. 55 These cut-out portions 9 do not extend the full length of the sleeve portions but termi-

nate short of the cuff ends thereof. At the other ends of the cut-out portions 9, curved edges 12 are formed to correspond with the curved edges 6 of the body portion of the 60 coat. Opposite said curved edges 12 the pocket flaps 11 are formed from the material left by cutting said curved edges.

In making up the coat, the lateral edge portions of the body 1 are folded inward 65 toward each other, and the upper parts of the sleeve portions together with the breast portions 3 are folded down to bring said breast portions into position for their curved edges 8 to be secured to the curved edges 7 70 of the body portion. The opposite edges of the cut-outs 9 are secured together as shown in Fig. 2, and the curved edges 12 are secured to the curved edges 6 under the arms as shown in Fig. 3. The straight edges 5 are 75 lapped by the pocket flap carrying edges 10, as shown in Fig. 2, said pocket flaps 11 being arranged as also shown in this figure. The lower edges 13 are secured to the upper edges 14 of the sleeve portions as shown in 80 Fig. 3 to complete the sleeves. Of course, any suitable form of collar may be attached to the coat around the neck opening 4, as suggested in dotted lines in Figs. 2 and 3.

It will be observed that the pattern is so 85 fashioned that it may be cut from a rectangular piece of material with very little waste, because the sleeve portions project very slightly beyond the lateral edges of the body portion, and the breast portions 3 90 extend only slightly above the sleeve portions. The shoulders of the coat are entirely free from seams, and such seams as are necessary are located where moisture will not be apt to collect and penetrate. The 95 provision of the breast portions 3 eliminates the necessity of making seams extending entirely across the front of the coat at the line of the pocket flaps 11, and gives the garment a neater appearance as well as increases its 100 wearing qualities.

The breast portions 3 have lateral extensions 30 adapted to supplement lateral extensions 31 on the bottom of the body portion to form the facings or flies as shown 105 more clearly in Fig. 4. It will be understood that in making up the coat the extensions 30 and 31 are folded on their adjacent portions 3 and 1, respectively, along the dotted lines in Fig. 1.

While the coat is illustrated with certain 110 kinds of trimmings, it should be understood

that said trimmings do not constitute any part of this invention and may, therefore, be changed at will without departing from the invention.

5 Having thus described my invention, what I claim as new and desire to secure by Letters Patent of the United States is:—

1. A coat comprising in a single piece the body portion, sleeve portions and breast portions, the sleeve portions having cut-outs extending longitudinally thereof and terminating short of the cuff ends thereof for the purpose specified.

2. A coat comprising in a single piece the body portion and sleeve portions, the latter having cut-outs extending longitudinally thereof and terminating short of the cuff

ends thereof for the purpose specified, and integral pocket flaps formed out of material left by cutting the sleeve portions.

20

3. A coat comprising in a single piece the body portion and sleeve portions, the latter having cut-outs extending longitudinally thereof and terminating short of the cuff ends thereof, curved edges extending from the other extremities of said cut-outs and designed to fit under the arms, and pocket flaps formed out of material left by cutting the sleeve portions opposite said curved edges and adjacent the longitudinal cut-outs.

25

30

In testimony whereof I have signed my name to this specification.

PHILIP BRASLOWSKY.
